KELLY BUSHING

Blasito Bronzan, Los Angeles, and Glenn D. Johnson, Compton, Calif., assignors to Baash-Ross Tool Company, Los Angeles, Calif., a corporation of California

Application May 23, 1938, Serial No. 209,522

10 Claims. (Cl. 255—23)

This invention relates to well drilling apparatus and relates more particularly to bushings for use in the rotary tables of well drilling rigs. A general object of this invention is to provide 5 an improved, dependable and effective drive bushing or Kelly bushing for use in a rotary table.

In the rotary method of deep well drilling a rotary table is provided at the derrick to drive or rotate the drilling string. A drill stem or kelly 10 of polygonal cross section is provided on the upper end of the drilling string and operates in what is known as a Kelly bushing in the rotary table. The engagement of the Kelly bushing with the kelly is such that rotation is transmitted from 15 the rotary table to the kelly and the kelly is capable of vertical movement through the bushing while the rotation transmitting engagement is maintained. The kelly and the Kelly engaging parts of the bushing are subjected to severe 20 wear and as a result slap and play soon develop between the bushing and the kelly. If this condition is not corrected the drive stem or kelly may be irreparably damaged.

Another object of the invention is to provide a 25 Kelly bushing embodying novel means for adjusting its Kelly engaging parts to maintain them in correct engagement with the drill stem or kelly.

Another object of this invention is to provide a 30 Kelly bushing embodying simple, practical and easily operated means for adjusting the several stem or Kelly engaging parts to preserve the correct engagement thereof with the kelly.

Another object of this invention is to provide a 35 Kelly bushing embodying groups or series of rotatable rollers, each series operating to engage a face of the polygonal kelly and separate means for adjusting the series of rollers to maintain a uniform engagement of the rollers with the faces of the kelly and to assure a well distributed transmission of forces, thereby greatly reducing wear 40 and the accompanying play and looseness.

Another object of this invention is to provide a 45 Kelly bushing of the character mentioned in which separate carriers or cages are provided to support one or more series of rollers and each cage is independently adjustable by simple manipulation of a screw to bring its rollers into proper contact with the kelly.

Another object of this invention is to provide a 50 Kelly bushing of the character mentioned in which each cage and its respective rollers and adjusting means form a unit that may be conveniently handled, serviced, etc.

Another object of this invention is to provide a 55 Kelly bushing of the character mentioned in

which the adjusting means are positive and serve to maintain their respective cages and rollers in given or set positions until the adjustments are subsequently changed.

A further object of this invention is to provide 5 an adjustable Kelly bushing in which the Kelly engaging parts may be adjusted quickly and with a minimum of labor.

The various objects and features of our invention will be fully understood from the following 10 detailed description of a typical preferred form and application of the invention, throughout which description reference is made to the accompanying drawings, in which:

Fig. 1 is a side elevation of the improved 15 Kelly bushing provided by this invention engaged about a kelly and seated in a rotary table, illustrating the rotary table in a central vertical section. Fig. 2 is an enlarged fragmentary plan view taken as indicated by line 2—2 on Fig. 1 20 showing the kelly in cross section. Fig. 3 is a vertical detailed sectional view of the Kelly bushing taken as indicated by line 3—3 on Fig. 2. Fig. 4 is a horizontal detailed sectional view taken substantially as indicated by line 4—4 on Fig. 3. 25 Fig. 5 is a rear elevation of one of the cages and its adjusting element removed from the body and Fig. 6 is a top or plan view of the assembly shown in Fig. 5.

The bushing of the present invention is intended 30 primarily for use in the rotary table of a well drilling apparatus to drive or rotate the drilling string. In the following detailed description we will describe the bushing of the invention employed in a typical rotary table to engage or drive 35 a drill stem or kelly of octagonal transverse cross section. It is to be understood that modifications or changes may be made in the bushing of the invention to adapt it for use with other forms of well drilling equipment and that the particular 40 application of the invention illustrated is not to be construed as limiting or restricting the use or scope of the invention.

The typical rotary unit illustrated in Figs. 1 45 and 2 of the drawings includes a rotary table T rotatably supported on a race or support 40 through a suitable bearing 41. A driven pinion 42 meshes with ring gear teeth 43 on the under side of the table T to rotate the table. The table T is provided with a central vertical opening 44 and a master bushing B is fitted in the opening 44 50 to rotate with the table T. The master bushing B has a central vertical opening 45 whose upper portion is polygonal or square in transverse cross section. The portion of the opening 45 imme- 55

diately below its polygonal part is conical or tapered. The improved bushing of the invention is adapted to be seated in the opening 15 to engage or drive a kelly K. The stem or kelly K illustrated is an elongate member of octagonal transverse cross section having eight flat vertical faces F. The kelly K extends centrally and vertically through the table and bushing assembly and may be considered as connected with the well drilling string.

The improved Kelly bushing of the invention may be said to comprise, generally, a body 16 to be seated in the opening 15, a plurality of cages 17 in the body 16 for engaging the kelly K and means 19 associated with the cages 17 for adjusting them with respect to the kelly K to obtain the correct engagement of the rollers 18 with the kelly.

The bushing body 16 is a tubular structure or member for carrying the cages 17 and the other parts of the bushing. The body 16 is shaped to seat in the opening 15 of the master bushing B. The lower part 20 of the body 16 is round in horizontal cross section and is tapered 25 to fit in the tapered portion of the opening 15. The adjacent portion of the body 16 is polygonal or square in external configuration to fit the square portion of the opening 15 whereby the Kelly bushing rotates with the table T. The upper portion 21 of the body 16 is round or cylindrical in external configuration for the purpose to be hereinafter described. Four 30 equally spaced laterally projecting lugs 22 are provided on the exterior of the body 16 immediately below its cylindrical upper portion 21. The longitudinal opening of the tubular body 16 is shaped and proportioned to receive the cages 17 and their adjusting elements. The major upper portion of the body opening is 35 polygonal having four main flat vertical walls 23 disposed at right angles to one another and corner walls or diagonal walls 24 lying in vertical planes and connecting the adjacent main walls 23. An annular internal or inwardly projecting flange 25 is provided on the body 16 at the lower ends of its walls 23 and 24 to support the cages 17.

The cages 17 form supports or carriers for the rollers 18 and are arranged in the tubular body 16 to have their rollers contact the faces F of the kelly K. The cages 17 may be identical and may be integral one-piece members. In the construction illustrated the cages 17 are frame-like members having flat parallel upper 50 and lower ends 26 and 27, respectively, and flat parallel opposite sides 28. The lower ends 27 of the cages 17 are adapted to rest on the flange 25 and the upper ends 26 of the cages lie in a plane slightly above the upper end of the bushing body 16. The outer faces of the cages 17 with respect to the central axis of the bushing are of special formation, as will be subsequently described. The inner side of each cage 17 has two angularly related or convergent vertical 55 faces 29. Vertical openings or slots 30 are provided in the cages 17 to hold or receive the rollers 18. In the form of the invention illustrated there are two slots 30 in each cage 17. The slots 30 have their ends spaced from the upper 60 and lower ends 26 and 27 of the cages 17 and extend horizontally through the cages from between their inner and outer sides. The side walls of the slots 30 are preferably flat and substantially parallel and in the construction 65 illustrated extend outwardly at right angles to

the adjacent inner faces 29 of the cages 17. The inner corners of the cages 17 have angular parts 31 and the parts 31 of the adjacent cages 17 are in nesting or meshing relation as clearly illustrated in Figs. 2 and 4 of the drawings. It is preferred that the parts 31 of the adjacent cages 17 have substantial clearance whereby the cages may be independently adjusted toward and away from the central vertical axis of the bushing.

The rollers 18 are the kelly engaging parts of the bushing. The rollers 18 may be identical and are cylindrical tubular parts with flat parallel ends. In accordance with the invention there is a plurality or series of vertically spaced 15 rollers 18 in each slot 30. The rollers 18 are supported in the slots 30 to rotate about substantially horizontal axes. The means for supporting the rollers 18 include shafts or pins 32 arranged in openings 33 in the cages 17. The openings 33 intersect the slots 30 and the pins 32 extend through the tubular rollers 18 and have their opposite end portions supported in the openings 33. The rollers 18 are freely rotatable on their respective pins 32. The pins 32 20 may be secured in their openings 33 in any suitable manner, for example they may be pressed or force-fitted in the openings. The rollers 18 of a set or series are vertically spaced 25 apart to be independently rotatable. The ends 30 of the rollers 18 have suitable working clearance with the flat vertical side walls of the slots 30. In accordance with the invention the rollers 18 project slightly from the inner angular faces 29 of the cages 17 to cooperate with the kelly 35 K. There is a series of rollers 18 for engaging each flat face F of the polygonal kelly K. This assures an effective distribution of turing forces throughout the circumference of the kelly. The rollers 18 are preferably of substantial length 40 to have extensive engagement with the faces F of the kelly K.

It is preferred to provide means for lubricating the rotatable rollers 18 so that the engagement of the rollers with the kelly offers a minimum of resistance to vertical movement of the kelly K through the bushing. The inner ends of the aligned pin supporting openings 33 are in communication. Vertical lubricant ports 35 extend into the cages 17 from their upper ends and intersect the communicating inner end parts of the openings 33 to deliver lubricant to the openings. Longitudinal lubricant ports 36 enter the pin 32 from their inner ends and conduct the lubricant from the openings 33 to 50 lateral ports 37. The lateral ports 37 in the pins 32 discharge the lubricant into the openings of the tubular rollers 18 to lubricate the rollers. Suitable grease gun fittings 38 are provided at the upper ends of the ports 35 to facilitate the introduction of lubricant under pressure to the lubricant port systems. The grease gun fittings 38 are preferably recessed in the upper ends 26 of the cages 17.

The means 19 for adjusting the cages 17 to 65 obtain the correct contact of the rollers 18 with the kelly K are important features of the invention. The adjusting means 19 are in the nature of wedge means and each includes a gib or wedge element 39 associated with a cage 17. The elements 39 are plate-like members arranged between the outer sides of the cages 17 and the opposing walls 23 of the body 16. The outer sides of the elements 39 are flat and have sliding or shifting engagement with the body 75

faces 23. Each element 39 has a rib 40 extending along one vertical edge. Each rib 40 has a diagonal face 41 cooperating with a diagonal body face 24 and each rib has two vertical surfaces 42 disposed at right angles to one another, one surface 42 cooperating with the side 28 of the related or connected cage 17 and the other surface 42 cooperating with a side 28 of an adjacent cage 17 and the vertical edge or side of the element 39 on said adjacent cage. The ribs 40 serve to hold the cages 17 and the elements 39 against lateral movement and thus assist in locating the assembly in the body 16. The elements 39 are vertically shiftable in the body 16 and are vertically shiftable with respect to their respective cages 17. It is to be observed that the elements 39 with their ribs 40 form positive means for the transmission of torque between the body 16 and the cages 17 and yet allow or produce shifting of the cages 17 toward and away from the central vertical axis of the bushing with no possibility of movement of the cages 17 at right angles to the movement just mentioned.

25 Connections are provided between the shiftable adjusting elements 39 and their respective cages 17 whereby the cages 17 and their adjusting elements may be handled as units. These connections include vertical slots 43 in the adjusting elements 39 and pins or screws 44 threaded in openings in the cages 17 and extending out through the slots. The heads of the screws 44 serve to prevent separation of the elements 39 from their cages 17. The heads of the screws 44 are preferably recessed in the outer sides of the elements 39.

The adjusting means 19 further include wedge parts on the cages 17 and the adjusting elements 39 whereby vertical movement of an element effects lateral adjustment of its respective cage 17. There is preferably a series of wedge parts 45 on the outer side of each cage 17 and a complementary or cooperating series of wedge parts 46 on the adjacent or connected adjusting element 39. The wedge parts 45 and 46 have flat active faces sloping downwardly and inwardly relative to the central vertical axis of the bushing. The wedge parts 45 preferably extend horizontally across the outer sides of the cages 17 and the wedge parts 46 may extend across the inner faces of the elements 39 from their ribs 40 to their remote longitudinal edges. The outer sides of the adjusting elements 39 normally bear on the body walls 23 and the wedge parts 46 normally cooperate with the wedge parts 45 so that the elements 39 serve to support the cages 17 against outward movement and transmit forces between the cages and the body 16. It will be seen that upward movement of the elements 39 relative to the cages 17 effects inward movement of the cages and that downward movement of the elements 39 with respect to the cages permits outward movement of the cages. The wedge parts 45 and 46 present broad extensive cooperating faces and the series of wedge parts extend between the upper and lower ends of the cages 17 and elements 39 so that the cages are dependably supported and maintained in vertical positions.

70 The adjusting means 19 further includes screw means for adjusting or shifting the elements 39 vertically to effect the lateral adjustment of the cages 17. A retaining ring 47 is threaded on the cylindrical upper portion 21 of the body 16 and has an inwardly projecting annular flange 48

overlying the upper end of the body. A ring 49 is arranged against the upper ends of the cages 17 and is engaged by the flange 48 of the ring 47. The ring 47 acting through the medium of its flange 48 and the ring 49 serves to hold the cages 17 against upward movement. Screws 50 are passed through openings 17 in the ring 49 and are threaded into sockets 52 in the elements 39. The screws 50 are in the nature of cap screws each having a head 53 cooperating with the upper side of the ring 49. It will be seen that rotation of the screws 50 in one direction feeds or moves the associated adjusting element 39 upwardly and that threading of the screws in the other direction allows the element 39 to 18 lower or settle by gravity. The screws 50 are located so that their heads 53 are adapted to engage the inner peripheral surface of the flange 48. This engagement serves to prevent turning of the screws 50. Notches 54 are provided in the flange 48 and the ring 47 is adapted to be turned to a position where its notches 54 oppose or are aligned with the screw heads 53. With the ring 47 in this position the heads 53 are free to be turned so that the screws 50 may be rotated or 25 threaded to adjust the cages 17. It is to be observed that the heads 53 of the adjusting screws 50 are readily accessible at the upper end of the bushing.

It is preferred to provide means for locking 30 or setting the ring 47 in a position where its notches 54 are out of alignment with the screw heads 53 so that the screws are prevented from turning and the adjustment of the cages 17 is maintained. The retaining ring 47 is split or 35 provided with a lateral slot 55. Outwardly projecting lugs 56 are provided on the ring 47 at the opposite sides of the slot 55 and a bolt 57 is passed through openings in the lugs 56. Two outwardly projecting ears 60 are provided on the 40 ring 47 and are located to be above two of the lugs 22 when the notches 54 are out of alignment with the screws 50. Pins or bolts 61 are passed through openings in the aligned lugs 22 and ears 60 to secure the ring 47 against turning. When the bolt 57 is tightened the ring 47 is clamped tightly to the upper portion 21 of the body 16 and when the bolts 61 are arranged in place the ring is positively held against turning.

In the preferred construction the above described ring 49 is split or divided into two sections so that the screws 50 serve to connect two cages 17 and their respective adjusting elements 39 with each half or section of the split ring. This facilitates the handling of the cages and 55 the adjusting elements.

It is believed that the operation of the improved Kelly bushing of the present invention will be readily understood from the foregoing detailed description. During drilling operations the table T is rotated in the usual manner and the rollers 18 cooperating with the faces F of the Kelly K transmit the rotation to the Kelly and drilling string. The Kelly K may be fed 60 vertically through the bushing as it is rotated. The freely rotatable rollers 18 offer a minimum of resistance to this vertical movement of the Kelly K. The cages 17 are normally held in position where their rollers 18 are in correct engagement with the Kelly K by the adjusting elements 39. The adjusting elements 39 in turn are held in position by the screws 50 and the flange 48 of the ring 47 serves to prevent loosening or turning of the screws. Accordingly, the 75

setting or adjustment of the cages 17 is maintained indefinitely.

When it becomes desirable or necessary to adjust the cages 17 to compensate for wear or to fit the bushing to the kelly K, the bolts 61 are removed and the bolt 57 is loosened whereupon the ring 47 is turned to a position where its notches 54 are adapted to receive the screw heads 53. In practice the ring 47 may be threaded upwardly to relieve the downward pressure on the cages transmitted from the ring 47 through the ring 49. The screws 50 may be easily turned to effect vertical movement of the elements 39 and thus produce inward or outward shifting of the cages 17 as desired. In adjusting the cages 17 to obtain the correct engagement of the rollers 18 with the kelly K it may be found desirable to thread the several screws 50 upwardly until the rollers 18 obtain such a firm contact with the kelly K that the kelly is adapted to raise the bushing through this engagement. The screws 50 may then be backed off or loosened slightly until the kelly K slides freely through the bushing when raised. It is to be observed that the screws 50 may be individually manipulated to obtain the desired or correct engagement of the rollers 18 of the individual cages 17 with the Kelly faces F. Following the adjustment of the cages 17 the ring 47 is turned to a position where its notches 54 are out of alignment with the screw heads 53 and the bolt 57 is then tightened and bolts 61 are passed through the openings in the lugs 22 and ears 60 to secure the ring in this position. The screws 50 are then locked against turning, as described above, so that the cages 17 are definitely held in the adjusted positions. The cages 17 may be adjusted from time to time during the use of the bushing to prevent the development of excessive play between the kelly K and the bushing rollers 18.

Having described only a typical preferred form and application of our invention, we do not wish to be limited or restricted to the specific details herein set forth, but wish to reserve to ourselves any variations or modifications that may appear to those skilled in the art or fall within the scope of the following claims.

Having described our invention, we claim:

1. A bushing for a rotary table to drive a drill stem of polygonal cross section comprising a body to be carried by the table and having an opening for passing the stem, parts in the opening for contacting the stem, shiftable carriers for the said parts, means holding the carriers against vertical movement in the opening and supporting the carriers for substantially horizontal movement toward and away from the stem, and means for shifting the carriers substantially horizontally to positions where their said parts cooperate with the stem to transmit rotation thereto, said means including vertically movable adjusting elements cooperating with the carriers and means for actuating the said elements.

2. A bushing for a rotary table to drive a drill stem of polygonal cross section comprising a body to be carried by the table and having an opening for passing the stem, parts in the opening for contacting the stem, shiftable carriers for the said parts, and means for shifting the carriers to positions where their said parts cooperate with the stem to transmit rotation thereto, said means including vertically shiftable wedge elements in the opening cooperable with the walls thereof and the carriers, and screw means for shifting the wedge elements.

3. A bushing for a rotary table to drive a drill stem of polygonal cross section comprising a body to be carried by the table and having an opening for passing the stem, parts in the opening for contacting the stem, shiftable carriers for the said parts, and means for shifting the carriers to positions where their said parts cooperate with the stem to transmit rotation thereto, said means including vertically shiftable adjusting elements bearing against the wall of the opening, cooperable wedge parts on the carriers and elements, and means for shifting the said elements.

4. A bushing for a rotary table to drive a drill stem of polygonal cross section comprising a body to be carried by the table and having an opening for passing the stem, parts in the opening for contacting the stem, carriers for the said parts shiftable horizontally in the opening, and means for adjusting the carriers to have their said parts in correct contact with the drill stem comprising vertically shiftable wedge elements cooperating with the carriers, and means for operating the wedge elements vertically.

5. A bushing for a rotary table to drive a drill stem of polygonal cross section comprising a body to be carried by the table and having an opening for passing the stem, carriers shiftable in the opening, pluralities of rotatable rollers carried by the carriers to engage the stem, and means for maintaining the rollers in cooperation with the stem comprising a shiftable adjusting element associated with each carrier, cooperable tapered parts on the carriers and their associated elements, and means for individually shifting said elements.

6. A bushing for a rotary table to drive a drill stem of polygonal cross section comprising a body to be carried by the table and having an opening for passing the stem, carriers shiftable in the opening, rotatable rollers on the cages for cooperating with the stem to rotate the same, wedge elements for shifting the cages to bring their rollers into correct cooperation with the stem, screws for shifting the wedge elements, and a member on the body normally preventing turning of the screws.

7. A bushing for a rotary table to drive a drill stem of polygonal cross section comprising a body to be carried by the table and having an opening for passing the stem, carriers shiftable in the opening, rotatable rollers on the cages for cooperating with the stem to rotate the same, wedge elements for shifting the cages to bring their rollers into correct cooperation with the stem, screws for shifting the wedge elements, and a turnable ring on the body normally preventing turning of the screws and turnable to a position where the screws are free to be turned.

8. A bushing for a rotary table to drive a drill stem of polygonal cross section comprising a body to be carried by the table and having an opening for passing the stem, carriers in the opening, means supporting the carriers for horizontal movement, an adjusting element shiftably carried by each carrier, rollers on the carriers for cooperating with the stem, cooperable wedge parts on the carriers and their elements, a member holding the carriers in the opening, screws threaded in the elements and reacting against said member to shift the elements whereby the wedge parts act to shift the carriers, and means normally locking the screws against turning.

9. A bushing for a rotary table to drive a drill stem of polygonal cross section comprising a body to be carried by the table and having an opening

for passing the stem, carriers in the opening, means supporting the carriers for horizontal movement, an adjusting element shiftably carried by each carrier, rollers on the carriers for cooperating with the stem, cooperable wedge parts on the carriers and their elements, a member holding the carriers in the opening, screws threaded in the elements and reacting against said member to shift the elements whereby the wedge parts act to shift the carriers, and means normally locking the screws against turning, said means including a ring threaded on the body to hold the member in place and engageable by the screws to prevent turning of the same.

10. A bushing for driving a polygonal drill stem comprising a body having an opening for passing the stem, cages in the body opening shiftable toward and away from the central vertical axis of the bushing, wedge elements bearing between the walls of the opening and the cages and shiftable to move the cages, parts carried by the cages for cooperating with the stem to transmit rotation thereto, cooperating surfaces on the wedge elements and cages for the transmission of torque between the body and cages, and means for shifting the wedge elements to adjust the cages.

BLASITO BRONZAN.
GLENN D. JOHNSON.
